UNITED STATES PATENT OFFICE.

KATHERINE HELEN McFARLAND, OF CHICAGO, ILLINOIS.

CORSET ATTACHMENT.

SPECIFICATION forming part of Letters Patent No. 759,542, dated May 10, 1904.

Application filed December 17, 1903. Serial No. 185,601. (No model.)

To all whom it may concern:

Be it known that I, KATHERINE HELEN McFARLAND, a citizen of the United States, residing at Chicago, in the county of Cook and State of Illinois, have invented a new and useful Corset Attachment, of which the following is a specification.

This invention relates to garment stays or retainers, and it is particularly adapted for holding or retaining the front part of a shirt-waist, so as to effectually produce the "dip-front" effect.

Another object is to provide a stay which will be capable of engagement with the opposing adjacent fastening-stays of a corset, so that the liability of the unclasping of the corset while being worn will be avoided, thus insuring the proper position of the waistband at all times.

A further object is to provide means for quickly removing and attaching the stay or retainer, as well as to provide one which will efficiently perform the service without producing an unsightly appearance.

Further objects and advantages of this invention will appear in the following description, and the novel feature thereof will be particularly pointed out in the appended claims, it being understood that changes in the form, proportion, and the minor details of construction may be resorted to without departing from the spirit or sacrificing any of the advantages of this invention.

In the drawings, Figure 1 is a fragmentary detail view of a pair of adjacent fastening-stays with my invention applied. Fig. 2 is a similar view of the stays with the retainer detached. Fig. 3 is a detail perspective view of the retainer. Fig. 4 is a transverse sectional view of my invention applied, and Fig. 5 is a plan view of the retainer-blank.

The numerals 1 and 2 designate the two adjacent opposing fastening-stays for a corset, each of which is provided with a transverse bar 3, having an intermediate offset constituting a loop 4. These bars are designed as fastening devices for engagement with a garment-stay, which also serves as means for locking the two corset-stays together. The

bars are intended to be placed below the waist-line of the corset, and the stay or retainer engaging them consists of a flexed strip 5 of sheet metal having an intermediate straight portion 6, with a downwardly-disposed hook-shaped terminal 7 at its upper end, while at the lower end are two parallel upwardly-disposed locking-tongues 8 and 9 for engagement with the offset loops 4. The tongues 8 and 9 are slightly yieldable and lie closely adjacent to the straight intermediate portion, so that the offset loops of the bars 3 will be frictionally engaged between the tongues and the adjacent surface or wall of the intermediate portion 6.

Inasmuch as the engaging tongues 8 and 9 are spaced apart so as to engage the respective bars on the opposing corset-stays, the stays will be efficiently secured together, so as to avoid all liability of the corset becoming accidentally unclasped.

The downwardly-disposed terminal 7 is slightly curved, so as to snugly fit over the skirt-band, and thus prevent an appearance of a protuberance at the point of the connection of the retainer and stay with the corset.

The bars 3 can be applied to any preferred type of corset to suit the figure of the wearer, and after adjusting the corset the retainer will be moved into locking engagement with the loops on the bars.

The draw-string or tape in the body-garment (such as a shirt-waist) should then be drawn tight and tied under the hook of the retainer. The waistband of the outer skirt should then be moved under the hook, which will snugly clamp it against the wall of the straight intermediate portion, after which the belt can be adjusted without displaying any portion of the retainer.

Having thus described my invention, what I claim, and desire to secure by Letters Patent, is—

1. The combination with two adjacent corset-fastening stays having loops upon the faces thereof, of a garment-retainer having upwardly-extending tongues to engage said loops, and a downwardly-disposed skirt-band-engaging hook.

2. The combination with the adjacent corset-fastening stays, of loops on the respective stays, and a garment-retainer having yielding tongues to bind the loops between the 5 tongues and the adjacent portion of the retainer.

In testimony that I claim the foregoing as

my own I have hereto affixed my signature in the presence of two witnesses.

KATHERINE HELEN McFARLAND.
